UNITED STATES PATENT OFFICE.

OSCAR HEITZMANN, OF ST. LOUIS, MISSOURI, ASSIGNOR OF ONE-HALF TO DEIDRICH H. STEINEKE, OF ST. LOUIS, MISSOURI.

LONGITUDINAL AND TRANSVERSE ARCH SUPPORT.

Application filed July 14, 1923. Serial No. 651,454.

To all whom it may concern:

Be it known that I, OSCAR HEITZMANN, citizen of the United States, residing at St. Louis, in the State of Missouri, have invented certain new and useful Improvements in Longitudinal and Transverse Arch Supports, of which the following is a specification.

This invention relates to arch supports and the primary object of the invention is to provide a device of this kind that is particularly adapted for the prevention and correction of broken down transverse arches of the ball of the human foot.

Another object of the invention is to provide an arch support which effectively supports the longitudinal and transverse arches of the human foot and which will prevent the breaking down of the shanks of shoes.

A further object is to provide a construction which is simple, efficacious and comfortable in use, and that may be made at a low cost.

With the above general objects in view, and others that will become apparent as the nature of the invention is better understood, the same consists in the novel form, combination and arrangement of parts hereinafter more fully described, shown in the accompanying drawing and claimed.

In the drawing, wherein like reference characters indicate corresponding parts throughout the several views,

Figure 1 is a top plan view of an inner sole having an arch support applied to the under surface thereof, which is constructed in accordance with the present invention,

Figure 2 is a bottom plan view of the device shown in Figure 1,

Figure 3 is a longitudinal sectional view taken substantially upon line 3—3 of Figure 1, and

Figure 4 is a transverse sectional view taken on line 4—4 of Figure 1.

Referring more in detail to the drawing, the present invention is shown applied to the under surface of an ordinary inner sole 5 and consists of an upper plate 6 of suitable rigid material such as tempered steel. This plate is of a length to extend from the forward part of the heel to a point beneath the inner metatarsal bones of the foot and is

preferably formed with a narrower central portion so as to avoid discomfort due to pressure upon sensitive portions of the foot at this point.

The plate 6 is preferably attached to the insole 5 by means of rivets 7 or the like, and the forward end thereof is broadened and formed with an upwardly directed hump 8 adapted to give support to the transverse arch of the foot under the inner metatarsal bones, or between the first and fifth metatarsals. The hump 8 is preferably formed to occupy a major portion of the width of the forward end of the plate 6 and gradually tapers narrower rearwardly and also gradually merges with the plane of the rear portion of the plate as shown in Figure 1, so that this hump is of substantially arch shape in plan as shown in Figure 1, thereby accurately fitting the arch of the foot between the first and fifth metatarsal bones in such manner as to insure comfort to the wearer and proper support of the arch. It will also be noticed that the outwardly curved side of the hump is located at the outer side of the insole and that the major dimension of the hump is located with its axis parallel with the longitudinal axis of the insole. By forming the bump in this manner, more efficient and satisfactory results have been obtained than is had by the use of segmento-spherical humps such as have been used in prior devices of this nature.

It will be noted that the forward end of the plate 6 terminates rearwardly of the point of flexure of the foot so as to not interfere with the ease of walking, and as this plate is curved slightly in a longitudinal direction, it will provide ample support for the longitudinal arch. Also, by reason of the stiff material from which plate 6 is formed, it will act as a shank stiffener for preventing breaking down of the shanks of shoes.

A longitudinal relatively narrow spring plate 8' is disposed beneath the plate 6 and has its rear end attached as at 9, by riveting or the like, to the rear portion of the plate 6 just forwardly of the rear end of the latter, and the forward end of this plate 8' is provided with a hump 10 substantially of the same form as the hump 8 of the plate 6, but of slightly smaller size so that the forward end of the plate 8' will have a sliding bearing upon the under surface of the

2

hump 8, and will be guided in the latter for movement longitudinally of the insole. Obviously, in use, the central portion of the, thereof, will be flexed downwardly so as to occupy a normal position in slightly spaced relation to the plate 6, whereby when the weight is placed upon the support this plate will yield upwardly and tend to straighten for giving the desired cushion effect. By providing the plate with interfitting, forward ends in this manner, it is only necessary to provide one rivet for attachment of the two plates to each other and the forward end of the spring plate is effectively guided and held against lateral swinging.

An extremely simple, durable and efficient form of longitudinal and anterior or transverse arch support is thus provided, and it will of course be apparent that the insole will be formed with a hump in conformity to the shape of the hump of the plate 6 when these parts are used conjointly.

Minor changes may be made without departing from the spirit and scope of the invention as claimed.

What I claim as new is:—

In a shoe, a support located in the shank thereof, said support including an upper plate having a rear end portion, an intermediate portion concaved longitudinally and transversely, and a front end portion connected to the intermediate portion by a hump, and a second plate applied to the under side of the first mentioned plate and extending under the intermediate portion thereof and partially under the forward end thereof, the said second plate being humped similarly to the first mentioned plate and having its upper surface in close contact with the lower surface of the first mentioned plate, the second mentioned plate being secured at its rear end to the first mentioned plate at the concaved intermediate portion thereof, the forward ends of said plates being disconnected from each other, whereby the plates may flex with relation to each other, in the manner and for the purpose specified.

In testimony whereof I affix my signature.

OSCAR HEITZMANN.
